(57) **CLAIM**

What is claimed is an ornamental design for a wireless speaker, as shown and described.

DESCRIPTION

FIG. 1 depicts the top-right-front perspective view of the wireless speaker, the shape and surface ornamentation of which are intended to resemble an audio-cassette tape cartridge.

FIG. 2 depicts the bottom-right-rear perspective view of the wireless speaker of FIG. 1.

FIG. 3 depicts the front view of the wireless speaker of FIG. 1.

FIG. 4 depicts the rear view of the wireless speaker of FIG. 1.

FIG. 5 depicts the top view of the wireless speaker of FIG. 1.

FIG. 6 depicts the bottom view of the wireless speaker of FIG. 1.

FIG. 7 depicts the left-side view of the wireless speaker of FIG. 1; and,

FIG. 8 depicts the right-side view of the wireless speaker of FIG. 1.

The broken lines shown in the Figures depict portions of the wireless speaker that form no part of the claimed design.

1 Claim, 4 Drawing Sheets
